[57] **CLAIM**

The ornamental design for a loudspeaker, as shown and described.

DESCRIPTION

FIG. 1 is a front elevational view of a loudspeaker showing my new design;

FIG. 2 is a right side elevational view thereof, the left side, top and bottom views being identical;

FIG. 3 is a rear elevational view thereof;

FIG. 4 is a sectional view thereof taken along line 4—4 of FIG. 1; and,

FIG. 5 is a sectional view thereof taken along line 5—5 of FIG. 2.

The broken line showing of speaker components are for illustrative purposes only and forms no part of the claimed design.

FIG. 1

FIG. 2

FIG. 3

FIG. 4

FIG. 5
